UNITED STATES PATENT OFFICE.

LOUIS ROTHSCHILD, OF PHILADELPHIA, PENNSYLVANIA, AND EVERETT G. CLEMENTS,
OF WASHINGTON, DISTRICT OF COLUMBIA.

DISPENSING APPARATUS AND MEANS FOR OPERATING SAME.

Application filed September 24, 1926. Serial No. 137,594.

Our invention relates broadly to the combination of an article dispensing apparatus and a door latching mechanism, and more specifically to a coin controlled door lock, such as is in general use on public toilet doors, and an article dispensing apparatus adapted to be operated to dispense an article upon the operation of the coin controlled door lock mechanism.

10 "Pay toilets" are in common use in most all public buildings and stations, and comprise the usual toilet rooms or booths, the doors of which are locked by a suitable coin controlled lock mechanism which require the deposit of a suitable coin before a user may operate the latch to gain entrance to the room or booth. The denomination of the coin required to release the latch entitles the user of the room to certain supplies 20 which are usually stored in bulk inside each room, or furnished as required, by a paid attendant.

Although it has been found to be most practical to require such a prepayment plan 25 for the use of the toilet rooms and such supplies as soaps, towels, combs, paper, etc., considerable loss is often suffered by operators of such toilets, due to theft and unscrupulous use of the supplies by the occupants of the rooms, or by the paid attendants who are charged with keeping the rooms stocked and in an orderly and sanitary condition.

It is therefore the primary object of our 35 invention to automatically vend to each occupant of a toilet room, upon the operation of the prepayment locking mechanism, a package containing one assortment of toilet supplies.

40 A further object of our invention is to provide a package vending machine operable by the actuation of the coin controlled door lock mechanism to dispense a package within the confines of the toilet room.

45 Other objects of our invention will be apparent by reference to the following specification and claims.

50 Referring now to the accompanying drawings which are made a part hereof, and on which similar reference characters indicate similar parts;

55 Fig. 1 is a perspective view of a series of toilet rooms or booths, equipped with the usual partitions and hinged doors, one of which doors is shown opened, to illustrate the

location of the dispensing machine and its operative connection with the door latch mechanism.

Fig. 2 is a side elevation, partly in section, of a coin controlled lock showing the bolt operating means for operating the dispensing machine.

Fig. 3 is a transverse section taken through the lock, door and operative mechanism of the dispensing machine, showing the operative connection between the lock and dispensing machine, and,

Fig. 4 is a section on line 4—4 of Fig. 3 showing the pawl and ratchet drive connection with the dispensing machine.

In the drawings the portions designated as A represent partitions which form the side walls of a series of toilet rooms or booths,

B the front wall panels, to which doors C are hinged as at D, and E the coin controlled door locks. All these portions, constituting the usual pay toilets, may be of any well known or approved construction or design, provided they do not depart from the spirit of our invention.

To the inner face of the hinged doors C we have shown a package dispensing machine 1, having a lateral housing extension 2, through which the inner door latch operating handle shaft 3 extends. Also journaled within the housing 2 is a similar shaft 4 which extends parallel with the shaft 3 through the door C, and into the lock housing E on the outer face of the door.

A pinion 5 is secured to the outer end of the shaft 4, within the lock housing E, and meshes with a rack 6 carried by the usual coin controlled latch or bolt mechanism 7 of the lock. Within the housing 2 of the dispensing machine 1 are slidably mounted two nut-members 8 and 9, through which the shafts 3 and 4 are threaded. The upper faces of each nut member is recessed to receive pivotally mounted pawls 10 and 11, which are normally held extended from the upper face of the nuts by leaf springs 12.

Above the nut members 8 and 9 is journaled a shaft 14 which extends at right angles to the shafts 3 and 4, and serves to operate a dispensing receptacle 15 in the dispensing machine 1. Secured on the shaft 14 is a pair of ratchet wheels 16 and 17, the teeth of one wheel being radially spaced with relation to the teeth of the other wheel, and the wheels 16 and 17 being positioned im-

mediately above the nut members 8 and 9 and pawls 10 and 11 respectively.

It will thus be seen that, upon operation of the outer latch handle 18, after deposit of a suitable coin in the slot 19 of the lock E, the latch or bolt mechanism will be reciprocated to withdraw the outer end of the bolt from the keeper 20, and simultaneously rotating the shaft 4 through the engagement 10 of the rack 6 with the pinion 5.

This rotation of the shaft 4 causes the threaded inner end to back the nut 8 in the housing 2, moving the pawl 10 rearwardly against a tooth of the ratchet wheel 16, oscillating the shaft 14 until the pawl has passed beyond the end of the ratchet tooth.

The dispensing receptacle 15 is thus turned to deliver a package into a suitable receiving tray below the dispensing machine, as is usual in machines of this character.

As a shaft 14 is oscillated as above explained, the ratchet wheel 17 is turned to bring a tooth into position in the path of the pawl 11, which is carried by the nut 9.

When the occupant of the toilet room actuates the inner handle secured on the inner end of the shaft 3, to again retract the bolt to permit the door to be opened, the shaft 3 is turned in the nut 9, backing the nut on the shaft and oscillating the shaft 14 through the action of the pawl and ratchet wheel as above explained. The dispensing receptacle is thus turned to a position within the machine 1 to receive another package which

cannot be dispensed until a suitable coin has been placed in the lock mechanism and the handle 18 again actuated. In Fig. 4 we have shown the nut 9 moved forward in dotted lines on the shaft 3.

What we claim is:

1. In combination with a door latch mechanism and an article dispensing device, actuating means for the dispensing device operatively connected to said latch mechanism, whereby said dispensing device actuating means is operated upon actuation of said latch mechanism.

2. In combination with a door latch mechanism, an article dispensing device, and common means for simultaneously operating said latch mechanism and said dispensing device.

3. In combination with a movable door, a latch mechanism therefor, a dispensing device carried by said door, and actuating means for the dispensing device operatively connected to said latch mechanism.

4. In combination with a movable door, a latch mechanism carried thereby, an article dispensing device carried by said door and having operative connection with said latch mechanism, and manually operated means for simultaneously operating said latch mechanism and said dispensing device.

In testimony whereof we affix our signatures.

LOUIS ROTHSCHILD.
EVERETT G. CLEMENTS.
